(22) Filed: Aug. 29, 2018

(57) CLAIM

(80) Hague Agreement Data

The ornamental design for a monitor for data processing device, as shown and described.

Int. Filing Date: Aug. 29, 2018

DESCRIPTION

Int. Reg. No.: DM/103593

1. Monitor for data processing device

Int. Reg. Date: Aug. 29, 2018

1.1 : Perspective

Int. Reg. Pub. Date: Mar. 1, 2019

1.2 : Front

(51) LOC (12) Cl. 14-03

1.3 : Back

(52) U.S. Cl.

1.4 : Left

USPC D14/127; D14/373

1.5 : Right

(58) Field of Classification Search

1.6 : Top

USPC D14/127, 129, 316, 336, 371, 373–377;

1.7 : Bottom

D6/641, 642, 685, 686; D16/200, 202,

1.8 : Perspective

D16/203, 208; D20/10, 18, 19, 21

1.9 : Enlarged

CPC G06F 1/626; H04N 5/64; H04N 5/645;

This article is a monitor having four screens which are arranged perpendicularly; reproduction 1.9 is an enlarged view of reproduction 1.8; the dot-dash broken lines in reproduction 1.9 form no part of the claimed design.

H05K 5/0204
